W. R. RIOUX.
SCREW CUTTING DIE,
APPLICATION FILED DEC. 8, 1916.

Patented Mar. 27, 1917.

William R. Rioux.
Inventor.

By

Marion Marion
Attns

UNITED STATES PATENT OFFICE.

WILLIAM R. RIOUX, OF MONTREAL, QUEBEC, CANADA.

SCREW-CUTTING DIE.

1,220,460.

Specification of Letters Patent. Patented Mar. 27, 1917.

Application filed December 8, 1916. Serial No. 135,781.

To all whom it may concern:

Be it known that I, WILLIAM R. RIOUX, a subject of the King of Great Britain, residing at Montreal, Province of Quebec, 5 Canada, have invented certain new and useful Improvements in Screw-Cutting Dies; and I do hereby declare that the following is a full, clear, and exact description of the invention, such as will enable others skilled 10 in the art to which it appertains to make and use the same.

The present invention relates to a die and more particularly to a screw cutting die adapted to cut left or right handed threads 15 upon a bolt or rod, and an object of the present invention is to provide a die of this character whereby the die cutters or chasers may be easily and readily projected to the desired angle for giving clearance and the 20 heel of the chasers may be projected radially toward the center of the die which will eliminate any undue friction and thereby increasing the efficiency of the die.

With the above and other objects in view 25 which will hereinafter appear as the description continues, the invention consists of the novel features of construction, combination and formation of parts as will be hereinafter more fully described and particularly pointed out in the appended claims.

In the accompanying drawings has been shown the simple and preferred form of the invention, it being, however, understood that no limitation is necessarily made to the precise structural details herein exhibited, but the right is hereby reserved to any changes, alterations or modifications to which recourse may be had that come within the 35 scope of the claims without departing from the spirit of the invention or sacrificing the efficiency of the same.

In the accompanying drawings:

Figure 1 is a plan view of the die embodying the present invention; and,

45 Fig. 2 is a vertical section through the same taken on the line 2-2 of Fig. 1 in the direction of the arrows as shown.

Referring now more particularly to the accompanying drawings wherein like and 50 corresponding parts are designated by similar reference characters throughout the several views.

The die forming the subject matter of the present invention comprises a ring preferably made of a single piece of metal having the screw chasers formed integral there-

with, but at the same time adapted to be adjacent to the desired angle without impairing the strength or efficiency of the die.

The numeral 1 indicates a ring which may 60 be split as at 2 so that it may readily fit any chuck or case and projecting radially toward the center of the ring and formed integral therewith are the screw chasers which are shown preferably three in number. Each of these screw chasers comprises a foot or web portion 3 which are formed to give to the chasers the required strength, and it is, of course, to be understood that as great an amount of metal may be left to 70 enlarge these foot portions, as is desired. Formed within the outer faces of the foot portions 3 are the laterally extending thread cutting edges 4. Formed within each of the web portions 3 of the chasers are the 75 diagonally extending slots 5 which extend through the web portions having an enlarged aperture 6 formed at the foot thereof and formed within the web portions adjacent the outer ends of the slots is an enlarged circular aperture 7 through which a tapered pin, screw or other peening device 8 may extend.

The diagonally extending slots 5 do not in any manner impair the strength of the 85 web portions of the chasers, but by inserting a peening device such as a tapered plug within the opening 7 the screw cutting edges will be thrown to the desired angle so as to give the eye of the die the required clearance and at the same time the foot portions of the cutting edges will be moved readily 90 toward the center of the die.

Whereas in the drawings I have shown a substantially truncated conical pin, it is, of 95 course, to be understood that this pin may be in the nature of a screw adapted to be threaded within the aperture 7 or any other suitable tapering peening device may be used.

Having thus fully described my invention, what I claim as new and desire to secure by Letters Patent is:

1. A die of the character described comprising a body portion, a plurality of screw 105 chasers formed integral therewith, the base portion of said chasers having diagonally extending slots formed therein and means adapted to be inserted within said slots for moving said chasers to different angles substantially as and for the purpose specified.

2. In a die of the character described

comprising a ring, a plurality of inwardly projecting screw chasers formed integral therewith, the base portions of said screw chasers each having a diagonally extending slot therein and having one end terminating at one side of said screw chasers, and tapered plugs adapted to be inserted within said slots for the purpose specified.

- 5 3. In a die of the character described comprising a split ring, a plurality of chasers formed integral therewith, each of said chasers comprising a web portion, each of said web portions having a diagonally extending slot formed therein and extending 10 transversely throughout each web portion, and a tapered pin adapted to be inserted within each of said slots adjacent the open ends thereof substantially as and for the purpose specified.
- 15 4. In a die of the character described

Copies of this patent may be obtained for five cents each, by addressing the "Commissioner of Patents, Washington, D. C."

comprising a split ring, a plurality of radially extending screw chasers formed integral therewith, each of said screw chasers comprising a web portion having screw cutting edges formed at and extending 25 transversely across the outer ends thereof, said web portions each having a diagonally extending slot formed therein and extending transversely throughout each web portion, the inner end of each of said slots terminating in an enlarged aperture, the opposite ends of said slots each having an enlarged transversely extending aperture communicating therewith, and a tapered pin adapted to be inserted within each of said 30 enlarged apertures substantially as and for the purpose specified.

In witness whereof I have hereunto set my hand.

WILLIAM R. RIOUX.
